United States Patent

Des. 235,153
Patented May 20, 1975

235,153

TENNIS BALL THROWER

Hector O. Conde, 6637 Cutting Blvd.,
El Cerrito, Calif. 94530

Filed Aug. 31, 1973, Ser. No. 393,323

Term of patent 14 years

Int. Cl. D21—02

U.S. Cl. D34—5 N

FIG. 1

FIG. 2

FIG. 3

FIG. 4FIG. 1 is a front elevational view of a tennis ball throwing device of the present invention.

FIG. 2 is a side elevational view thereof, the opposite side being a mirror image of that shown.

FIG. 3 is a rear elevational view thereof.

FIG. 4 is a perspective view in isometric thereof.

I claim:

The ornamental design for a tennis ball thrower, as shown and described.
